FIG. 3

INVENTOR.

HENDRIX K. CALDWELL

BY

A.B.Bonham
ATTORNEY

UNITED STATES PATENT OFFICE

HENDRIX K. CALDWELL, OF SAN DIEGO, CALIFORNIA

GROUNDING CLAMP

Application filed May 7, 1929. Serial No. 361,239.

My invention relates to grounding clamps, and the objects of my invention are: first, to provide a grounding clamp whereby a positive and lasting connection between the ground wire of an electric circuit and a water-pipe, gaspipe or other grounded pipe, is ensured; second, to provide a ground clamp which grounds the wire conduit as well as the ground wire; third, to provide a grounding device which is easy to install without the aid of special tools; fourth, to provide a grounding device which has a minimum number of parts; fifth, to provide a grounding device which is rigid and sturdy of construction, and sixth, to provide a grounding clamp which is simple of construction, durable, efficient in its action, and which will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawings and to the characters of reference thereon which form a part of this application, in which:

Figure 1 is a top or plan view of my grounding device; Fig. 2 is a sectional view thereof through 2—2 of Fig. 1 with the grounded wire shown in elevation; Fig. 3 is an end elevational view thereof with the lower clamp segment and wedging cap removed; and Fig. 4 is a perspective view of the clamping plug.

Similar characters of reference refer to similar parts and portions throughout the several views of the drawings.

Clamp jaws 1 and 2, screws 3, nipple 4, wire clamping plug 5, wedging cap 6, constitute the principal parts and portions of my grounding clamp.

Two clamping jaws 1 and 2 are provided each of which is semi-circular in cross section. These clamping jaws are adapted to extend along a grounded pipe G, such as a waterpipe or gaspipe a sufficient distance for forming a satisfactory contact therewith. The clamping jaws 1 and 2 are provided with

oppositely disposed lugs 1a and 2a, respectively, at each of their corners. These lugs are provided with aligned holes for receiving screws 3, each of which is adapted to receive a washer 3a and a nut 3b so that said screws 55 may rigidly secure said clamp jaws around the grounded pipe G.

A nipple 4 is integrally connected through a neck portion 4a with the upper clamp jaw 2, as shown best in Figs. 2 and 3 of the drawings. The nipple 4 is provided with a bore 4b therethrough which extends substantially at right angles and transversely to the axis of the ground clamp jaws 1 and 2. The one end portion 4c of this bore 4b is internally threaded for receiving the end of an electric wire conduit C, as shown best in Fig. 2. The other end of the nipple 4 is reduced in diameter and externally threaded, as indicated by 4d. The externally threaded portion 60 4d has an outer diameter similar to the inner diameter of the internally threaded portion 4c so that a conventional conduit cap member adapted to be normally screwed on the end of a conduit C may be screwed on to the threaded portion 4d. The portion of the bore 4b extending within the externally threaded portion 4d is tapered so that the walls thereof diverge towards the extended end of said externally threaded portion 4d 65 forming a wedging surface 4e.

A wire clamping plug 5 is provided with a tapered portion 5a corresponding to the tapered portion 4e so that said plug tends to wedge when forced in the wedge portion 4e 75 towards the conduit C. The plug 5 is provided with a slit 5b which bifurcates the plug except for a small narrow web 5c located at the inner or smaller end and to one side of said plug, as shown best in Fig. 2. The plug 5 is provided with a center, longitudinally extending bore 5d which is intersected longitudinally by the slit 5b. The bore 5d has a flared portion 5e at the inner or smaller end of the plug, as shown best in Figs. 2 and 4. 80

A wedging cap 6 is adapted to screw on the external threads 4d and force the plug 5 into the wedging portion 4e of the nipple 4. The insulation I from the grounding wire W 100 is removed from the end thereof and the wire

W inserted into the longitudinally extending bore 5d of the wire clamping plug 5, the flared portion 5e of said bore facilitating the insertion of the wire therein. The bore 5d before the plug is wedged, forms a snug but easily sliding fit with the wire W so that the plug may be placed on the end of the wire without the aid of tools. The plug is then inserted in the wedge portion 4e of the nipple and the cap 6 is screwed down until the closed end 6a thereof bears against the extended end of the plug 5 forcing said plug into the wedge and constricting the bore 5d by reason of the slit 5b, thereby rigidly and securely clamping the wire W.

It is preferred that the plug 5 be made out of copper or bronze or similar material which is relatively soft and will tend to form a good contact with the wedge portion 4e and top portion 6a of the cap. The cap 6 may be a conventional conduit pipe cap but it may be provided with a slight recess 6b in its closed end 6a so that the wire W may protrude slightly from the plug, thus the wire although not cut perfectly flush with the end of the plug 5 will not interfere with the action of the cap 6.

Though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

1. In a device of the class described, a grounded pipe clamp means, a nipple integral therewith, the one end of said nipple adapted to receive an electric conduit, said nipple provided with a bore continuing from said conduit, said bore diverging as it extends from said conduit forming a wedging surface, a plug means adapted to clamp a wire extending through said conduit and into said bore, and means for wedging said plug into said bore.

2. In a device of the class described, a nipple member, means for grounding said nipple member, said nipple member provided with a bore therethrough, an internally threaded portion at the one end of said nipple for receiving the end of a wire conduit, a tapered plug having longitudinal slits, said slits adapted to receive a wire extending from said conduit into said nipple, means for wedging said plug into the bore of said nipple whereby said wire is clamped within said slit.

3. In a device of the class described, a nipple integral with a member of a pipe clamp, said nipple provided with a bore therethrough

extending transversely to the pipe clamp, an internally threaded portion at the one end of said bore adapted to receive the end of a wire conduit, a tapered plug having an opening extending therethrough adapted to receive a wire extending from said conduit, said plug bifurcated along said opening except for a small linking portion, and means for wedging said plug into the bore of said nipple so as to clamp said wire and form a positive electrical connection between said wire and said nipple.

4. In a device of the class described, a nipple integral with a member of a pipe clamp, said nipple provided with a bore therethrough extending transversely to the pipe clamp, an internally threaded portion at the one end of said bore adapted to receive the end of a wire conduit, a tapered portion at the other end of said bore, a plug tapered to correspond to the tapered portion of said bore, said plug provided with an opening therethrough for receiving a wire extending from said wire conduit, said plug bifurcated longitudinally with said opening except for a small linking portion, and means for wedging said plug into the tapered portion of said bore so as to form a positive contact between said wire and said nipple.

5. In a device of the class described, a nipple integral with a member of a pipe clamp, said nipple provided with a bore therethrough extending transversely to the pipe clamp, an internally threaded portion at the one end of said bore adapted to receive the end of a wire conduit, a tapered portion at the other end of said bore, a plug tapered to correspond to the tapered portion of said bore, said plug provided with an opening therethrough for receiving a wire extending from said wire conduit, said plug bifurcated longitudinally with said opening except for a small linking portion, said nipple provided with an externally threaded portion surrounding the tapered end of said bore therethrough, and a cap means screwably mounted upon said external threads, said cap means adapted to bear against the one end of said plug and wedge said plug into the tapered portion of said bore and cause said plug to clamp said wire and form a positive contact therewith.

In testimony whereof, I have hereunto set my hand at San Diego, California this 17th day of April, 1929.

HENDRIX K. CALDWELL.
